UNITED STATES PATENT OFFICE.

OTIS E. BROWN, OF BROCKTON, MASSACHUSETTS, ASSIGNOR TO THE SINGER MANUFACTURING COMPANY, A CORPORATION OF NEW JERSEY.

STITCH-FORMING DEVICE.

1,152,482.

Specification of Letters Patent.

Patented Sept. 7, 1915.

Application filed October 19, 1911. Serial No. 655,519.

To all whom it may concern:

Be it known that I, OTIS E. BROWN, a citizen of the United States, residing at Brockton, in the county of Plymouth and State of Massachusetts, have invented certain new and useful Improvements in Stitch-Forming Devices, of which the following is a specification, reference being had therein to the accompanying drawings.

10 This invention relates to improvements in the means for handling the upper thread in sewing machines, and particularly in those employing a barbed or open-eyed needle and a coöperating loop-taker mounted upon the same side of the work; and it has for its object to provide effective means for laying the upper thread in the needle-eye in each stitch-forming cycle and insuring the proper presentation of the same for seizure by the 20 loop-taker.

In its preferred form, the machine is constructed with a laterally jogging needle-frame disposed beneath the work-support and having journaled therein a reciprocating needle-bar carrying the open-eyed needle, and the threading implement comprises an eyed member and a forked member spaced therefrom, both being sustained for independent adjustment upon a pivotally mounted carrier to which are imparted bodily lateral movements and oscillating movements for communicating to the threading implement successively operative movements transversely to and substantially within the 30 direction of the jogging movements of the needle for placing the upper thread within the needle-throat. The threading-implement actuating means are so connected with and controlled by the needle-frame jogging means, by means of which lateral feeding movements are imparted to the needle, that the operative movements of the threading-implement in the direction of feed correspond with the length of the feeding movements of the needle for all adjustments of the feeding mechanism. When the needle-eye and the path of movement of the loop-taker beak are arranged in parallel planes, a loop-spreader, preferably mounted upon the 40 needle-frame, is provided for carrying one

limb of a needle-thread loop drawn through the work by the needle for presentation for passage of the loop-taker beak.

The invention will be understood by reference to the accompanying drawings, in 55 which—

Figure 1 is a side elevation, with the frame in section, representing a wax-thread machine embodying the present improvements and constructed substantially in accordance 60 with my application 651,556, filed Sept. 27, 1911, and my Patent No. 1,097,389, of May 19, 1914; and Fig. 2 is a front end elevation of the same. Fig. 3 is a plan of certain parts of the machine with the frame omitted and 65 Fig. 4 an enlarged perspective view of the parts of the stitch-forming devices below the work-support. Fig. 5 is a perspective view of the two-member threading-implement and its carrier, and Figs. 6 and 7 are 70 detail views of the same partly in section upon different planes. Fig. 8 is a perspective view of a portion of the feeding mechanism, and Fig. 9 an enlarged perspective view showing the relative positions of the 75 upper-thread handling devices when the descending needle is near its extreme upper position. Fig. 10 is a perspective view of a portion of the needle-threading mechanism.

The frame is shown constructed with the 80 hollow base 1, the tubular standard 2 and the hollow overhanging arm 3 formed with the head 4 and having journaled therein the main-shaft 5 carrying the balance-wheel 6 and belt-pulley 7. The main-shaft has fixed 85 thereon by means of the set-screw 8 the hub 9 of the needle-actuating eccentric 10 embraced by the strap 11 and connected through the pitman 12 with one arm of the rocker 13 having a second arm 14 connected by means 90 of the pitman 15 with a crank carried by the needle-actuating rock-shaft 16. The rock-shaft 16 carries at its forward end a crank-arm 17 connected by the pitman 18 with a collar 19 fixed upon the needle-bar 20 95 carrying the barbed or open-eyed needle 21 and journaled in the bearing bosses 22^x of the jogging needle-frame 22. The needle reciprocates through the usual aperture in the throat-plate 23.

Coöperating with the needle in the production of stitches is the rotary shuttle 24 provided with the beak 24^x and having journaled eccentrically therein the thread-case 25. The shuttle is journaled in a suitable race 26 secured to the annular holder 27 whose foot-plate 28 is adjustably mounted upon the bed 1. The shuttle is actuated by means of the driver 29 which is 5 in practice secured upon the carrier 30 journaled in the holder 27 and provided with the peripheral gear-teeth 31 meshing with a driving gear 32 fixed upon the forward end of the shuttle-driver shaft 33 10 which is journaled in suitable bearings of the bed 1 and carries a bevel pinion 34 meshing with the larger bevel-wheel 35 fixed upon the upright shaft 36 within the standard 2 and carrying at its upper end 20 a bevel-pinion 37 meshing with a similar pinion 38 fixed upon the main-shaft 5. By the means just described, the shuttle receives two rotations for each rotation of the main-shaft and for each reciprocation 25 of the needle.

The feeding mechanism of the present machine is similar to that shown and described in my Patent No. 1,002,217, of September 5, 1911, and comprises a swinging 30 lever 39 having a forked rearward end 40 embracing the feed-actuating cam 41 fixed upon the upright shaft 36 and carrying at its upwardly offset opposite end a screw-stud 42 having a ball at one end embraced 35 by the recessed bearing washers 43 disposed between and journaled upon the adjacent faces of the yoke members 44 of a crank-arm 45 whose hub 46 is fixed upon the feed rock-shaft 47 journaled within and 40 longitudinally of the base 1. To prevent the endwise movement of the lever 39, the latter is provided with a depending stud 48 embraced by one end of a link 49 whose opposite end embraces the reduced lower end 45 of the upright shaft 36. The opposite faces of the lever 39 are formed intermediate the ends of the latter with segmental seats or guideways 39^x entered by the points of screw-studs 50 carried by the yoked central 50 portion 51 of the fulcrum-carrying lever 52 which is journaled upon the fulcrum-screw 53 sustained by the base 1. In practice the points of the screw-studs 50 enter slide-blocks fitted within the guideways 39^x, as 55 shown and described in my said Patent No. 1,002,217. The stud-screws 50 afford a fulcrum for the lever 39, and by shifting the lever 52 upon its fulcrum-stud 53 and varying the distance of the fulcrum 50 from the 60 actuating eccentric 41 the throw of the screw-stud 42, and consequently the degree of oscillation of the feed rock-shaft 47 may be varied. The outer end of the fulcrum-carrying lever 52 is formed with a fork in 65 which is pivotally mounted the catch-lever

54 pressed outwardly by a spring 55 secured upon the lever 52 so as to retain a tooth 54^x upon its lower end normally in operative relation with a toothed sector-plate 56 secured upon the base 1. By suitably operating the catch-lever 54 its tooth 54^x may be disengaged from the sector-plate 56 and the fulcrum-lever 52 shifted for adjustment of the length of feed. 70

The rock-shaft 47 is provided with an upwardly extending arm 57 having a transverse tubular boss entered by the stud-pin 58 tapped into the threaded aperture 59 in a lateral lug 60 of the needle-frame 22. At its opposite edge the needle-frame has a 80 split lug 61 carrying a stud-bolt 62 passing through a slot 63 in the guide member 64 formed in its rear side with a guideway to receive the slide-block 65 entered by the stud-bolt 62. The guide-member 64 is 85 formed at the upper end of an arm 66 rigidly secured upon the front end of the base 1 by suitable means.

Journalized in a rearwardly extending lug 67 of the bracket-arm head 4 is the vertically disposed threader rock-shaft 68 having rigidly secured upon its lower end the lateral crank-arm 69 carrying the stud 70 which enters a boss 71 of the swinging threader-carrier 72 which is provided with 90 a second boss 73 embracing a stud-pin 74 carried by a crank-arm 75 attached to the lower end of a rock-shaft 76 also journaled in the head of the bracket-arm. The rock-shaft 76 carries a lateral crank-arm 77 having journaled therein the stud-pin 78 whose head 79 is formed with a transverse aperture in which is secured the inwardly bent extremity 80^x of the pitman-rod 80 having secured upon its opposite end the yoke 81 carrying the alined center-screws 82 upon which is journaled the oscillating tubular bearing sleeve 83. Fitted within the bearing sleeve 83 is the rod 84 whose shouldered and threaded rearward end is tapped into the arm 85 rigidly attached to the vertical rock-shaft 86 which is provided with a second rigid arm 87 carrying the roller-stud 88 entering the cam-groove 89 of the cam-disk 90 whose hub 91 is secured by set-screws 92 upon the vertical shaft 36. The yoke 81 is provided with a second pair of center-screws 93 affording fulera for the transverse hub 94 at one end of a pitman-rod 95 whose opposite end is 100 adjustably secured in the collar 96 pivotally connected by means of the pin 97 with a lateral crank-arm 98 upon the vertical rock-shaft 99 having at its lower end the crank-arm 100 pivotally connected by the pin 101 with the rearward end of the bent link 102 having its opposite end pivotally connected by means of the stud-screw 103 with the fulcrum-lever 52. It will be seen that the 105 adjustment of the fulcrum-lever 52 to regu- 110

115

120

125

130

late the length of feed will, by the connections just described, turn the shaft 99 so as to shift the connection of the rearward end of the pitman-rod 80 with the arm 85 of the 5 rock-shaft 86, thereby simultaneously adjusting the throw of the threader-carrier under the action of it actuating cam 89.

The carrier 72 is shown provided with a 10 depending forked lug 72^x in which are adjustably secured the fastening ear 104 of the split socket 105 and the similar ear 106 of the split socket 107. The fastening ears 104 and 106 are pivotally mounted within the carrier-lug 72^x upon the common stud-screw 108, the former being secured in position thereon by means of the clamp-screw 109 passing through a slot 110 in the adjacent member of the lug and being tapped into the ear 104, while the ear 106 is clamped 15 adjustably against the inner face of the opposite member of the lug 72^x by means of the set-screw 111. The adjusting screws are so applied to the forked lug 72^x that they are both accessible from the front face 20 of the same.

Secured for endwise and circular adjustment in the socket 105 by means of the clamp-screw 112 is the shank of the eyed 25 threading member 113 formed in its downwardly offset lower extremity with the thread-aperture 114, and within the split socket 107 is secured for similar adjustment by means of the clamp-screw 115 the shank of the forked threading member 116 whose 30 downwardly offset lower end, laterally spaced from the apertured extremity of the eyed member 113 is formed with the thread-receiving notch 117, all as represented in Fig. 5. The split lugs of the sockets 105 35 and 107 are shown disposed in angular relation and the heads of the clamp-screws 112 and 115 are arranged at their forward faces, so as to be accessible for adjustment of the independently mounted members of 40 the threading implement from the front of the machine.

It will be observed that the carrier 72 is 45 journaled upon two stud-pins carried by independently mounted crank-arms 69 and 50 75, and thus acts as a link connection between the same. The parts are so related and actuated by the described connections with the actuating cam 89 that in the initial oscillatory movement of the rock-shaft 55 76 the carrier 72 is carried bodily forward until the stud 70 reaches a position substantially in alinement with the rock-shaft 76 and stud-pin 74, when its advance transversely to the direction of feed of the needle 60 is nearly arrested and the carrier is caused to swing upon the stud 70 in a direction substantially parallel with the needle-feeding movements. The primary advance movement of the spaced threading members 65 70 causes the movement of the strand of thread

extending between them toward the needle in whose eye it is placed before the feeding has proceeded to any considerable extent, and the final movement of the threader members substantially parallel with the lateral movements of the needle causes them to follow the needle in its operative feeding movements so as to insure against interference and disarrangement or breakage of the parts. In case the open side of the needle-eye is disposed toward the front of the machine, as represented in my pending application and Patent No. 1,097,389 before mentioned, when only a single eyed threader-arm is employed, the operative movements 70 of the latter may be controlled to correspond with the amplitude of feeding movements of the needle, so that the traverse of the threader is maintained at a minimum for all adjustments of the feeding mechanism. 75

Journaled in the bracket-arm head 4 is the vertical thread-controller rock-shaft 118 carrying at its lower end the bent thread-controller arm 119 formed at its outer end with a thread-engaging hook 119^x adapted to catch the needle-thread *n* extending between the work and the eye 114 of the threader-arm 113 and draw the same backwardly over the fixed and horizontally arranged thread-finger 120 in a substantially horizontal direction into the fork 117 of the threader-arm 116, as represented in Figs. 1 and 9. The rock-shaft 118 carries at its upper end a crank-arm 121 in which is journaled the pin 122 having a head 123 formed with a transverse aperture in which is secured the forward end of a pitman-rod 124 whose opposite end is similarly secured in the head 125 of a pin 126 journaled in the 90 outer end of a lever 127 mounted upon the fixed fulcrum 128 sustained by the bracket-arm and carrying intermediate its ends a roller-stud 129 adapted to enter the actuating cam-groove 130 in the cam-cylinder 131 95 100 fixed upon the main-shaft 5. The controller-arm 119 is so actuated by the cam 130 that it performs its operative thread-engaging movement just as the threader begins its advance needle-threading movement, seizing the slack thread given up by the take-up and laying the upper limb of the loop which it carries within the fork 117 of the threader-arm 116, and continuing its operative movement until it has drawn out all 105 the slack needle-thread. The controller-arm begins its return movement as the needle commences its descent, and gives up slack for the needle proportionate to the requirements of the latter during its descent 110 115 through the work, so as to prevent the rendering of the thread through the needle-eye and liability to breakage at such time. During the return movement of the controller arm and the descent of the needle the 120 125 130

eyed threader member 113 remains inactive so as to avoid any unnecessary pull upon the thread.

As set forth more fully in my application, and Patent No. 1,097,389 above mentioned, the take-up lever 132 is mounted upon the fulcrum-pin 133 and carries upon its rearwardly extending arm 134 the stud 135 embraced by the lower end of a link 136 whose upper end is entered by the stud 137 carried by the angle-lever 138 fulcrumed at 139 and carrying the roller-stud 140 which is adapted to enter the cam-groove 141 in the cam-cylinder 142 fixed upon the main-shaft 5. The needle-thread is led from the source of supply over certain guide-rollers mounted respectively upon and independently of the take-up lever 132 and finally over the guide-roller 132^x at the forward extremity of said lever and thence downwardly over a fixed guide-roller 143 and through the aperture 114 of the threader-arm 113 to the work, as represented in Figs. 1 and 9.

The material *m* is punctured for each stitch preparatory to the upward thrust of the needle for seizure of the upper thread by means of the awl 144 carried by reciprocating awl-bar 145 journaled in the head 4 of the bracket-arm. The material is pressed upon the work-support by the presser-foot 146 carried by the usual presser-bar journaled in the bracket-arm head 4 and provided with means for automatically lifting it preparatory to each lateral feeding movement of the needle occurring while the needle is in substantially its highest position.

Journaled in suitable bearing bosses 147 of the needle-frame 23 is the spreader-shaft 148 disposed substantially parallel with the needle-bar and formed at its upper end with a collar 149 in which is secured by means of the set-screw 150 the shank of the loop-spreader 151 whose laterally offset upper end is formed with a thread-engaging hook 152. The shaft 148 has secured upon its lower end the hub of a crank-arm 153 whose eyed outer end embraces the stud 154 secured in the apertured and split forward end of the pitman 155 in whose similarly split rearward end is secured the pin 156 entering an apertured boss 157 at the outer end of a lever 158 having at its opposite end a boss 159 into which is tapped the threaded lower end of the stud 160 formed with conical journals mounted in bearing bosses 161 upon the inner wall of the base 1. The lever 158 carries intermediate its ends the roller-stud 162 which enters the groove 163 of the cam-cylinder 164 fixed upon the needle-actuating rock-shaft 16. The horizontal vibratory movements imparted by the cam 163 to the lever 158 are transmitted through the described connections to the spreader rock-shaft 148 and are communicated by it to the

thread-engaging hook 152 of the spreader which moves in a path close to but at one side of the needle-path and serves to seize one limb of a thread-loop drawn down through the material by the needle and to spread the same near the inner face of the throat-plate 23 transversely of the plane of movement of the loop-taker beak 24^x, to enable the latter to enter the loop for the loop-casting operation, as represented in Fig. 4. 75 75

While the loop-spreader may be mounted and actuated in any manner suitable to enable it to perform its described function, in machines in which the needle has a lateral feeding movement it is desirable that it should be sustained by the jogging needle-frame in order that its relation to the needle may remain the same for all adjustments of the feed-actuating mechanism. 80

While various parts of the mechanism co-operating with the characteristic features of this improvement have been shown and described somewhat in detail herein, it is evident that the construction and arrangement of such parts are not material to the invention and also that the construction and arrangement of parts of the needle-threading and loop-spreading mechanisms may be considerably varied within the scope of the invention. 90 95

Having thus set forth the nature of the invention, what I claim herein is:—

1. In a sewing machine, the combination with a reciprocating open-eyed needle, and a loop-taker co-operating therewith, of a threading implement for inserting the upper thread in the needle-eye in each stitch-forming cycle, a carrier for said threading implement, a movable fulcrum for said carrier, and actuating means for the carrier whereby the latter in one stage of its movement acts to change the position of its fulcrum and in a second stage of its movement swings upon said fulcrum as an axis. 100 105

2. In a sewing machine, the combination with a reciprocating open-eyed needle, and a loop-taker co-operating therewith, of a threading implement comprising spaced eyed and forked members adapted for inserting the upper thread in the needle-eye in each stitch-forming cycle, a swinging carrier in which the component members of said threading implement are mounted for relative adjustment, an actuating cam, and an operative connection between the actuating cam and said carrier. 110 115 120

3. In a sewing machine, the combination with a reciprocating open-eyed needle, and a loop-taker co-operating therewith, of a threading implement comprising spaced eyed and forked members adapted for inserting the upper thread in the needle-eye in each stitch-forming cycle, a swinging carrier, sockets sustained by and relatively adjustable upon said carrier and each pro- 125 130

vided with means for adjustably securing therein one of said threading-implement members, and means for actuating said carrier to move the threading implement into 5 and out of operative relation with said needle.

4. In a sewing machine, the combination with a reciprocating needle-bar carrying an open-eyed needle, a laterally jogging frame 10 in which the needle-bar is mounted, and a loop-taker coöperating with the needle, of a threading implement mounted independently of said jogging frame and adapted for laying the upper thread in the needle-eye 15 in each stitch-forming cycle, feeding mechanism connected with said frame for imparting to the needle lateral work-feeding movements, feed-regulating means for determining the range of lateral feeding movements 20 of the needle, actuating means for said threading implement, and means for varying the operative movements of the threading implement to correspond with the range of feeding movements imparted to 25 the needle.

5. In a sewing machine, the combination with a reciprocating and laterally jogging needle-bar, a needle mounted therein and formed with an eye open on one side and arranged 30 in the direction of lateral jogging movements of the needle-bar, and a loop-taker coöperating with said needle, of a threading implement comprising spaced thread-holding members movable successively 35 transversely of the jogging movements of the needle-bar and then substantially in the same direction therewith and in paths upon opposite sides of the needle and adapted for laying the upper thread in the needle-eye in each stitch-forming cycle, feed-actuating mechanism from which the needle-bar derives the said jogging movements, feed-regulating means for determining the range of lateral jogging movements of the 40 needle-bar, actuating means for said threading implement, and means for varying the operative movements of the threading implement to correspond with the range of feeding movements imparted to the needle. 45

6. In a sewing machine, the combination with a reciprocating open-eyed needle and a loop-taker coöperating therewith, of a threading implement for inserting the upper thread in the needle-eye in each stitch-forming cycle, a carrier for said threading implement, two parallel rock-shafts, a crank-arm upon each of said rock-shafts pivotally connected with and adapted to support said carrier, and means connected 55 with one of said rock-shafts for actuating 60

the same and through said carrier the other of said rock-shafts.

7. In a sewing machine, the combination with a work-support, a reciprocating open-eyed needle, and a loop-taker coöperating therewith, of a threading implement comprising spaced eyed and forked members having a path of movement confined to a single plane transverse to the path of reciprocation of said needle, a vibratory thread-controlling member mounted upon a fixed fulcrum and adapted to engage the thread between the eyed threading member and the work-support and lay it in the fork of the other threading member, means for actuating said threading members for inserting the thread in the needle-eye, and actuating means for said thread-controlling member. 75

8. In a sewing machine, the combination with a reciprocating needle-bar carrying an open-eyed needle, a coöperating loop-taker provided with a loop-seizing beak, and a laterally jogging frame in which said needle-bar is journaled to reciprocate, of a threading implement movable toward and from 80 the path of movement of said needle and adapted to lay the upper thread in the needle-eye, a loop-spreader mounted upon and sustained by said laterally jogging frame and adapted to seize a limb of the loop of 85 thread drawn through the work by the needle and distend the same across the path of movement of the loop-taker beak, and means for actuating said loop-spreader. 90

9. In a sewing machine, the combination with a work-support, a reciprocating open-eyed needle, and a loop-taker coöperating therewith, of an eyed threading implement movable in a single plane transverse to the path of reciprocation of the needle, means 95 for moving said implement into threading position and for retracting the same after an interval of inaction during the movement of the threaded needle through the work, a vibratory thread controlling member mounted upon a fixed fulcrum and movable intermediate the work-support and said threading implement and adapted to coöperate with the latter in laying the thread in the needle-eye and adapted thereafter to release thread during the interval of inaction of the threading implement, and actuating means for said thread controlling member. 100 105

In testimony whereof, I have signed my name to this specification, in the presence of 115 two subscribing witnesses.
